UNITED STATES PATENT OFFICE.

ALBERT J. DEMMLER, OF WELLSVILLE, OHIO.

HOTBED FOR METAL-ROLLING.

SPECIFICATION forming part of Letters Patent No. 686,267, dated November 12, 1901.

Application filed August 4, 1900. Serial No. 25,857. (No model.)

To all whom it may concern:

Be it known that I, ALBERT J. DEMMLER, a resident of Wellsville, in the county of Columbiana and State of Ohio, have invented a new and useful Improvement in Hotbeds for Metal-Rolling; and I do hereby declare the following to be a full, clear, and exact description thereof.

My invention relates to an improvement in apparatus for rolling sheet metal, its object being to provide means for maintaining a pile of heated sheet or plate metal at approximately the proper heat for rolling and prevent such rapid cooling of the same as would render the sheets in the lower part of the pile too cool for the proper rolling and finishing.

The practice heretofore in the making of what is known as "blued" or "polished" sheet iron or steel has been to heat a pile of sheets or plates to practically the same as an annealing heat and at a certain temperature expose the sheets to the atmosphere, each sheet being exposed by turning it over and forming a pile of sheets by placing one turned-over sheet upon the other and then taking the pile to the rolls and passing between the same one or two sheets at a time while the sheets were over 300° Fahrenheit in heat, this being termed "warm-rolling" and being covered by Letters Patent No. 608,432, granted to W. M. Theobald August 2, 1898. One difficulty with this practice has been that the sheets in the lower part of the pile were liable to cool during the rolling of the sheets above them so as to be brought below the proper temperature for fixing the oxid on the surface or polishing the same.

The object of the present invention is to provide means for holding a mass or pile of sheets or plates at the proper temperature, so that the sheets in the lower part of the pile will not lose their heat so rapidly as to be lowered below the proper rolling temperature, the invention being intended for use in warm-rolling, either for bluing or polishing or in the rolling of the sheet or plate metal at higher temperatures, such as at a practically red heat to reduce the same to thinner gage, as set forth in companion application filed upon the same date, Serial No. 25,858.

To these several ends my invention consists, generally stated, in the combination, with a

set of sheet-rolls, of a hotbed adapted to support a pile of heated sheets or plates located in position to feed the same to the rolls, so that when the pile of sheets is placed thereon the hotbed will aid in maintaining the heat of the sheets in the pile as they are fed to the rolls.

It also consists in certain other improvements which will be hereinafter more particularly set forth and claimed.

To enable others skilled in the art to make and use my invention, I will describe the same more fully, referring to the accompanying drawings, in which—

Figure 1 is a longitudinal section of a set of rolls, showing the hotbed located in front of the same. Fig. 2 is a longitudinal section of a modified form of hotbed. Fig. 3 is a cross-section of the hotbed illustrated in Fig. 1, and Fig. 4 is a similar view of the hotbed illustrated in Fig. 2.

The different figures of the drawings illustrate some different forms of hotbeds suitable for employment in conjunction with the sheet-rolls, Fig. 1 showing an ordinary heated slab supporting the pile of sheets, and Fig. 2 a portable furnace having a heated slab or cover, the heat of which is maintained by the burning of fuel within the furnace.

The invention is employed with any suitable form of sheet-rolls 2, mounted in suitable housings 3, the hotbed being located in any suitable position convenient for feeding the sheets to the rolls—for example, as illustrated in Fig. 1, directly in front of the rolls.

The hotbed 4 (shown in Fig. 1) is formed of a suitable frame 5, supporting a heated metal slab 6, on which the pile of sheets 7 rests. This hot metal slab is preferably heated in the furnace with the sheets to be treated, as described in a companion application of even date herewith, Serial No. 25,856, the idea being to carry the sheets on the slabs on which they rest while being heated either in the furnace or within the annealing-box to the rolls, so that the sheets are not disturbed from the time that they are built up upon the slab and inserted in the furnace until they are fed directly to the rolls, the slabs thus forming the support for the sheets in the furnace and the means for carrying the same to the rolls and acting at the rolls as a hotbed

for maintaining the heat within the pile of sheets as the top sheets are fed one by one to the rolls. Such slabs are preferably made of cast-steel plates of sufficient thickness to fully support the sheets in handling and to store the necessary heat to maintain the mass of sheets in the pile at the proper heat for rolling.

The hotbed shown in Figs. 2 and 4 is a suitable portable furnace 8, carried on rollers 9 and preferably built of brickwork 10 within a suitable casing 11 and having extending over the top the slab 12, on which the pile of sheets rests. For the heating of the same I prefer to employ gas, and have illustrated a series of gas-jets 13 playing upon the slab and maintaining it at the proper heat. Where it is not practicable to use gas, a thin coke fire will serve the purpose, a grate 14 being shown for this purpose. The hotbed is made portable, so that it may be adjusted in position for the proper feeding of the sheets to the set of rolls, such position depending upon whether the sheets are to be simply warm-rolled, as above referred to, or whether they are to be hot-rolled and passed more than once between the rolls, in the latter case the hotbed being removably drawn back from the set of rolls or placed at one side thereof, as set forth in a companion application of even date here-with, Serial No. 25,858. In this construction the same supporting-slab on which the sheets rest when in the furnace may of course be employed as the top slab of the hotbed, the pile of sheets to be rolled being carried on such slab and placed upon the furnace or oven 8, by which through the heat applied to the under face of the slab such slab is held at any desired temperature and the pile of sheets maintained at a higher heat than if only the heat of the slab itself were depended on.

Each of the above-described forms of hotbeds may be used either in the manufacture of blued or polished sheet iron or steel, where the metal is preferably fed to the rolls at a black heat ranging from 300° upward, or may be used in the rolling of thin plate metal or of packs of sheets to reduce the same in thickness where the sheets are carried to the rolls while at a red heat, and the hotbed is utilized to maintain them practically at that tem-

perature until the entire pile of packs is rolled. In the latter case in order to further protect the pile of sheets or packs of sheets a suitable cover may be placed over the pile of packs, which can be raised by suitable power apparatus when each pack is to be withdrawn from the pile, such cover being illustrated in Fig. 4 at 18, in which case the slab 12 and the cover 16 may together form the annealing-box or sectional part of such box in which the pile of packs has been heated.

In the regular use of the invention either with warm or hot sheets the loss of heat from the pile, such as would prevent the proper rolling of the sheets or packs, is prevented through the heat passing from the hotbed on which the pile of sheets rests into such pile, as above described, so that in such rolling operation the sheets in any pile can be rolled at nearly the same temperature and a much larger proportion of perfectly-rolled sheets be obtained.

What I claim as my invention, and desire to secure by Letters Patent, is—

1. In combination with a set of sheet-rolls, a hotbed having a slab adapted to support a pile of heated sheets and located in position to feed the same to the rolls and means for heating the slab. 75
2. In combination with a set of sheet-rolls, a hotbed having a slab adapted to support a pile of heated sheets and located in position to feed the same to the rolls, and a fire-chamber under the slab. 80
3. In combination with a set of rolls, a hotbed having a removable slab adapted to support a pile of heated sheets and located in position to feed the same to the rolls. 85
4. In combination with a set of rolls, a hotbed having a slab adapted to support a pile of heated sheets and located in position to feed the same to the rolls, and a cover adapted to fit over and inclose the pile when supported on the hotbed. 90

In testimony whereof I, the said ALBERT J. DEMMLER, have hereunto set my hand.

ALBERT J. DEMMLER.
